PIPE SUPPORTING ARRANGEMENT

Sami R. Svendsen, Chicago, Ill., assignor to Pullman-Standard Car Manufacturing Company, Chicago, Ill., a corporation of Delaware

Application October 7, 1938, Serial No. 233,740

9 Claims. (Cl. 243—68)

This invention relates to pipe-supporting arrangements particularly for use on vehicles, and has for its primary object the provision of such an arrangement wherein expansion and contraction of the pipe is readily permitted without adversely affecting the pipe and in which the pipe is fully free to move without resistance but in fixed, spaced relation to a supporting member.

Other objects of the invention are the provision of a pipe-supporting arrangement affording adjustability with respect to the height of the pipe and/or number of pipes supported; individual and independently movable supports for each pipe when a plurality of pipes are used; pivotal supporting brackets with pivotal pipe clamps; and a pipe-supporting arrangement adapted to carry both heating and water supply pipes entirely independently of each other.

The foregoing and other objects are attained by the mechanism illustrated in the accompanying drawings, in which—

Fig. 1 is a view of a single heating pipe installation in a room supported in accordance with this invention and having water pipes also supported therewith.

Fig. 2 is a cross-sectional view taken on the line 2—2 of Fig. 1 showing the supporting bracket arrangement for the heating and water pipes;

Fig. 3 is an exploded perspective view of the supporting bracket showing the parts in disassembled relation; and

Fig. 4 is a cross-sectional view similar to Fig. 2 but illustrating an installation supporting a plurality of heating pipes.

In the drawings, 10 represents a railway car having a side frame including posts 11 and an underframe 12 supporting a floor 13. The car illustrated happens to be a room car, therefore the invention is disclosed as applied to a single room and consists of a single finned-pipe heating radiator 14 anchored, at one end, to side wall plate 9 secured to the posts 11 and carried, at the opposite end, by the supporting bracket of this invention. The radiator 14, at one end, is connected to a source of heating medium (not shown) by means of a feed pipe 15 and a return pipe 16, and, since it is anchored to the wall 9 at this same end by a bolt 17 taking the inlet and return fitting 18, movement due to expansion and contraction, as the heat is turned on and off, will occur at the opposite end of the radiator where it is carried in supporting bracket 20. The wall plate 9, where the bolt 17 enters, is reinforced on the back side by a tapping plate 19 into which the bolt is threaded to provide a rigid anchor.

To permit expansion and contraction of the pipe 14 without restraint, the bracket 20 provides a doubly pivoted joint accommodating all movement of the pipe while positively supporting it in spaced relation to the wall, as best shown in Fig. 2.

The bracket 20 is comprised of a number of parts, best shown in Fig. 3, and of which the support bar 21 forms the basic supporting member. The bar 21, at its lower end, is welded into a supporting and attaching bracket 22 which forms a means of securing the bar to the side wall by bolts 23 threaded into backing plate 24 and also acts as a support, as will hereinafter appear. At its upper end, the bar 21 is secured to a seat support angle 25 attached to the side wall and is tapped to receive a screw 26 extending through the horizontal flange of the angle which forms the connection therebetween. A swinging bracket 27 is pivotally associated with the bar 21 by means of bearing 28 encircling the bar and supported on spacing tube 29, also encircling the bar, and extends outwardly from the bar 21 to provide a bearing 30 for a pipe clamp 31 pivotally associated with the bearing 30 by means of a bolt 32 extending through the bearing and having a shoulder 33 against which the clamp is drawn by a nut 34. By providing the shoulder 33 on the bolt, the nut 34 is prevented from causing a binding action between the clamp 31 and the head on the bolt as the nut is drawn tight, so that a freely pivoting relationship between the bolt and bracket 27 is assured, whereby a doubly pivoted joint between the pipe clamp and supporting bar is afforded by the pivotal bearings 28 and 30. A spacer 29^b spaces the bearing 28 from the lower side of the horizontal flange of the angle member 25.

The pipe clamp 31 comprises a saddle 35 supporting the pipe 14 and seated about the shank of bolt 32 against the shoulder 33, and a clamp 36 disposed about the bolt in engagement with the pipe 14 and having a flanged end 37 engaging the saddle 35 edgewise and about which it fulcrums to tightly engage the pipe 14 as the nut 34 is drawn home. The pipe clamp 31 is rigidly clamped against the shoulder 33, and there is no relative movement between the pipe 14 and the clamp, nor between the clamp and the bolt—the only movement being pivotal movement of the bolt within the bearing 30, and it will be seen that by the provision of the double pivoted relationship between the pipe 14 and bracket 27 the pipe is free to expand and contract without frictional restraint of any kind.

Hot and cold water supply pipes 40 and 41, respectively, may also be carried by the bracket 20 and are equally adapted to ready movement without frictional resistance. A swinging bracket 42 carries both pipes and is supported on the bar 21 by a section 29^a of the spacing tube 29. The spacing tube section 29^a rests on the supporting bracket 22 and directly underlies pivot bearing 43 of the bracket 42 on which the tube 29 is supported. The swinging bracket 42, like 10 bracket 21, affords a doubly pivoted joint between the pipes and supporting bar 21. The bracket extends outwardly from the pivoted bearing 43 and is provided at its extremity with a bearing 44 in which pipe clamps 46 and 47 are pivotally supported by means of double-ended bolt 45. The pipe clamps 46 and 47 are exactly 15 like the pipe clamp 31, therefore a description of that clamp arrangement is equally applicable to the water pipe clamps which, accordingly, will not specifically be described. The bolt 45 is provided with shoulders 48 against which the pipe clamps are drawn in opposing relation by nuts 49 to provide sufficient clearance therebetween to 20 accommodate the bearing 44 without frictional resistance, thereby freely to permit expansion and contraction of the pipes without restraint.

A coil spring 50 is disposed about the bar 21 beneath the lower surface of the bearing 28 of bracket 27 and is seated on a washer 51 resting on the upper end of spacing tube 29 and exerts a constant pressure on all of the parts to insure a tight anti-rattle fit of all of the parts between the supporting and attaching bracket 22 and the horizontal flange of the angle member 25, but permits ready pivotal movement of the bracket 27 without the necessity for providing clearances between the various parts for that purpose, and while the spring, as shown, is disposed beneath the bearing 28, it might be otherwise in the assembly and still serve its purpose.

The heating pipe 14 and the water pipes 40 and 41, with all fittings and supports, are concealed by an ornamental grille 52 which is removable for access to the parts for maintenance and is supported on the angle 25 and forms a part of the side finish of the car.

While the invention has been described as applied to a single room, it is, of course, equally applicable to systems involving the use of pipes of greater length in which any number of the supporting brackets of this invention might be used to carry the pipe and permit expansion and contraction throughout the length thereof to any degree and without restraint, thereby to prevent buckling or distortion of the pipe. The heating and/or water pipes are adjustable with respect to their height from the floor merely by changing the length of the spacing members 29, 29^a, and 29^b, and, while only one heating pipe has been described as being carried by the supporting bracket 20, a plurality of heating pipes may be supported on the bracket, as shown in Fig. 4, wherein a plurality of swinging brackets 127 are pivoted on the vertical bar 121 and separated by the spring 150 disposed between the respective bracket pivot bearings 128, the lowermost of which is supported on the shorter spacing tube 129 resting on the pivot bearing 143 of water-pipe-supporting bracket 142 as before. Each of the brackets 127 supports a heating pipe 114, as before, and which may be independent of each other or a continuous pipe loop and of any length requiring any number of pivotal supporting brackets.

From the foregoing, it will be seen that there has been provided a pipe-supporting arrangement having pivotal means permitting longitudinal movement of the pipe due to expansion and contraction without binding action of any kind and supporting pipes of different expansion and contraction characteristics and in which the pipes are easily removable and replaceable without disturbing the supporting bracket assembly.

What is claimed is:

1. In a pipe-supporting arrangement for a plurality of pipes, a fixed vertically disposed supporting member, separate swinging brackets pivoted on said supporting member for independent movement in spaced horizontal planes for supporting individual pipes, brackets pivotally associated with said swinging brackets for supporting said pipes thereon, and spring-pressure means disposed between said swinging brackets.

2. In a pipe-supporting arrangement for a plurality of pipes, a supporting fixed vertically disposed member, a plurality of swinging pipe-carrying brackets pivoted on said supporting member for independent movement in spaced horizontal planes, brackets pivotally associated with said swinging brackets for supporting individual pipes thereon, spacing members disposed between and supporting said swing brackets, and spring means adapted to exert pressure between said spacing members and swinging brackets.

3. In a pipe-supporting arrangement, a supporting member comprising a vertical bar having a bottom supporting and attaching bracket and means for securing the upper end of the bar, a plurality of swingable brackets having bearings engaging said vertical bar for independent pivotal movement relative thereto, spacing members engaging said bar and disposed between, beneath and above said swinging brackets and supporting them from said attaching bracket, and a spring adapted to exert pressure between all of said members on said bar, said brackets having pivotal connection with individual pipe-engaging means carried respectively thereby.

4. In a pipe-supporting arrangement, a fixed vertically disposed supporting member, a swingable bracket having a bearing engaging said supporting member and movable in a horizontal plane thereabout, a spring adapted to exert pressure on said bearing, and a pipe-engaging member supported on said swingable bracket for pivotal movement relative thereto in a plane parallel to the plane of movement of said bracket.

5. In a pipe-supporting arrangement, a fixed supporting member, a bracket pivotally mounted with respect to said supporting member for swinging movement in a horizontal plane and having a bearing engaging said member, said bracket being adapted to support a plurality of pipes carried in pipe clamps disposed above and below said bracket and pivotally connected therewith.

6. In a pipe-supporting arrangement, a fixed supporting member, a bracket pivotally mounted with respect to said supporting member for swinging movement in a horizontal plane and having a bearing engaging said member, a pipe-hanger member pivotally supported on said bracket, another bracket pivotally mounted with respect to said supporting member for independent swinging movement in a horizontal plane and having a bearing engaging said member, said last named bracket being adapted to

support a plurality of pipes carried in pipe clamps disposed above and below said bracket and pivotally connected therewith.

7. In a pipe-supporting arrangement for pipes having different expansion and contraction characteristics, a fixed vertically disposed supporting member, a plurality of individual members mounted on the supporting member for independent movement in a plane disposed perpendicular thereto, and pipe-clamping means pivotally associated with and carried by each of said individual members.

8. In a pipe-supporting arrangement for pipes having different expansion and contraction

characteristics, a fixed supporting member, a plurality of individual members pivotally mounted on the supporting member for movement in a horizontal plane, and pipe-clamping means pivotally associated with and carried by each of said individual members.

9. In a pipe-supporting arrangement, a fixed vertically disposed supporting member, a swinging bracket mounted on said supporting member for pivotal movement in a horizontal plane, and a bracket mounted on said swinging bracket for pivotal movement in a horizontal plane relative thereto adapted to support a pipe.

SAMI R. SVENDSEN.

CERTIFICATE OF CORRECTION.

Patent No. 2,250,732.

July 29, 1941.

SAMI R. SVENDSEN.

It is hereby certified that error appears in the printed specification of the above numbered patent requiring correction as follows: Page 2, second column, line 13, claim 1, for "porting" read --supporting--; line 22, claim 2, strike out the word "supporting" and insert the same after "disposed" in line 23, same claim; line 29, same claim 2, for "swing" read --swinging--; and that the said Letters Patent should be read with this correction therein that the same may conform to the record of the case in the Patent Office.

Signed and sealed this 16th day of September, A. D. 1941.

Henry Van Arsdale,
(Seal) Acting Commissioner of Patents.
